UNITED STATES PATENT OFFICE

2,273,982

COMBINATION WRENCH AND DIE STARTER

Chester A. Ostas, Bedford, Ohio

Application July 27, 1940, Serial No. 347,907

1 Claim. (Cl. 81—72)

This invention has general reference to combination wrench and die starter devices ordinarily designed to engage in and rotate for purposes of removal, or the insertion of, short lengths of tubular parts from their normal seating, as well as for starting a die-nut to cut a screw-thread at the end of a pipe without the use of a conventional stock.

Such devices, as above specified, usually comprise a hollow body member housing radially active dogs for locking said device interiorly of the tubular part to be removed or inserted, with an exterior threaded portion for reception and operation of a screw-cutting die nut.

The primary object of this invention is to furnish an improved wrench and die starter of the indicated species characterized by a novel and more effective locking means whereby the general efficiency of such devices is increased.

Another object of this invention is the provision of a combination wrench and die starter characterized by opposed radially-shiftable locking dogs, with a coactive intervening and axially-movable expander-wedge component.

A further object of this invention is the provision of a combination internal wrench and screw-cutting die starter as indicated in the preceding paragraph, which is especially adapted for the removal of broken off portions of threaded pipe ends from fitting; as well as for re-threading the remaining portion of such broken off pipe to facilitate its re-connection to the fitting.

A still further object is the provision of a combination internal wrench and die-starter device which is simple in construction, easy to operate, positive in action, and comparatively cheap to produce.

Other objects with ancillary advantages of this invention will become apparent from the following detailed explanation of the preferred form illustrated by the accompanying sheet of illustrative drawings, wherein like reference characters designate corresponding parts in all the views; while the concluding claims more particularly recite the features of novelty over prior art.

In the drawing:

Fig. 1 is a longitudinal view of the wrench device of this invention in applied position for removal of a broken pipe end from a fitting, said pipe end and fitting being shown in section for purposes of clarity.

Fig. 2 is a longitudinal section of the wrench device and associated parts included in the preceding view, but drawn to a larger scale for

better illustration of details, said section being taken approximately on the plane II—II of Fig. 1.

Fig. 3 is a cross-section on the plane III—III of Fig. 2.

Fig. 4 is a perspective view of one of the dogs hereinafter fully explained.

Fig. 5 is a similar view of the expander wedge, later on explained in detail; and,

Fig. 6 is a view somewhat corresponding to Fig. 1, but showing the device in use for cutting a screw-thread on the end of a pipe by aid of an associated die-nut.

In describing the embodiment of this invention illustrated by the above captioned drawing, specific terms will be employed for the sake of clarity, but it is to be understood the scope of said invention is not thereby limited; each such term being deemed to embrace all equivalents which perform substantially the same function for an analogous purpose.

Referring now specifically to the drawing, it will be observed that the improved internal wrench and die-nut starter device of this invention, as illustrated, comprises a hollow body member 1 having a cylindrical bore 2, with a relatively reduced screw-threaded extension 3 and a plain terminal portion 4; while the remote end of the bore 2 is fitted with a removable closure-plug 5 having a semi-spherical head 6,

said plug being restrained against rotation by a set screw 7, in an obvious manner. The body-member 1 is also provided with an external screw-threaded part 8 and a polygonal-shaped manipulating head 9, later on again referred to.

In the plain or barrel portion 10, of the body member 1, are diametrically-opposed arcual slots 11, for reception of the complementary toothed portions or lugs 12 of radially-shiftable segmental members 13. Each segmental or locking member 13, as best understood from Fig. 4, more particularly, is of less than semi-circular cross-section transversely, with the toothed lug 12 projecting from the outer or cylindrically curved face 14, and an inner tapering surface defining with said curved face an inclined plane 15, circumscribed by the parallel segmental end chord edges 16, and the opposingly curved edges 17 formed by cutting the cylindrical portion, on a longitudinal plane inclined at an acute angle 50 with respect to the axis of the device.

Interposed between and coactive with the segmental locking members 13 is a tapered wedge 18 corresponding to that of said members; and as seen in Fig. 5 to best advantage, this wedge 18 has opposed inclined plane surfaces 19 re-

spectively engageable with the confronting faces 15 of the members 13, under the action of an expander stud 20 operative in the screw-threaded extension 8 of the bore of the body member 1. It is to be noted that the thread 21 on the stud 20 is conveniently left-handed, or directionally opposed to that of the body member part 8; also that the inclination of the faces 15 and 19 is such as to positively force the segmental members 13 radially outwards in parallel with the longitudinal axis of the internal wrench and die-nut starting device. It is also worthy of note that the expander stud 20 is formed with a manipulator head 22 and that the over all diameter across the teeth 23 on the lugs 12 is in excess of that of the bore of the barrel portion 10, so that when once assembled with the wedge 18 in said portion they are prevented from falling out even when the plug 5 is not in place, or should it be lost; also that the teeth 23 are pitched for left-hand activity in order to positively prevent rotation of the body member 1; when a die-nut threaded on the part 8, see Fig. 6, is turned for screw-threading the end of a pipe 24 externally, as conventionally shown in said figure.

From the foregoing, it will be readily understood that when it is desired to remove a broken-off portion 24', Figs. 1-3, of threaded pipe from a fitting 25, the plain barrel end 10 of the device of this invention is inserted in said portion 24' still remaining in the fitting 25, with the teeth 23 retracted inwardly of the arcual slots 11, by previous rotation of the expander stud 20 to the right-hand, and incidental release of the wedge 18 from "jamming" coaction with the inclined faces 15 of the segmental locking members 13. When the device is positioned as just stated, the operator rotates the expander stud 20 to the left-hand by suitable means until its inner end engages and axially forces the wedge 18 between the segmental locking members 13 radially outwards until the respectively opposing lug teeth 23 firmly grip into the bore of the pipe end 24; whereupon, by application of further rotary motion to the stud 20, it will be obvious that said pipe end can be readily withdrawn from the fitting 25. Obviously, by a reverse operation, after securing the teeth 23 into a screw-nipple and applying a wrench to the body member head 9, said nipple can be driven to the desired extent into an interiorly screw-threaded pipe or other desired location. Again it will be readily understood that the broken off pipe end 24' is removed without injury to the screw-thread in the fitting 25.

In order to facilitate re-threading of the pipe

24, the described device is introduced into the end thereof, as aforesaid, until the shoulder 8' of the screw portion 8 abuts the pipe end, then the expander screw 20 is rotated until the teeth 23 firmly grip into the inner wall, whereupon the appropriate die-nut 26, previously threaded on the screw 8 can be turned by a Stillson wrench and a new thread cut with ease and a minimum of labor. At this juncture, it will be noted that the screw-thread 8 on the body member 1 preferably conforms with that desired to be cut exteriorly of the pipe 24; also that when the die-nut 26 is initially started it will be correctly aligned with respect to the axis of the pipe 24 and thereby greatly facilitate the cutting of an accurate thread on said pipe.

It will furthermore be understood that minor changes in the size, form and various parts of the combined internal wrench and die starter of this invention may be made without departing from the spirit and scope thereof; as more tersely expressed in the following claim.

Having thus described my invention, I claim:

An internal wrench comprising a body member including a barrel section, with a removable closure at its entry end and a larger diameter externally screw-threaded portion, defining an abutment shoulder, with a manipulator head at the outer end of said portion; diametrically opposed arcual slots in the barrel section; complementary dog elements disposed lengthwise within the barrel section bore, and each of said elements being of sectoral cross-section with the curved face conformatory to that of the barrel section bore and having the chord face inclined at an acute angle relative to the longitudinal axis of the body member; a radially directed toothed lug medially projecting from the curved face of each dog element for projection through the associated arcual slot, said lug being of a circumferentially directed extent to provide substantial flanking portions of the curved face; an individual wedge embodying opposed cylindrical walls concentrically related to the barrel bore and intermediate inclined faces complementary to and shiftable with respect to the corresponding coactive faces of the dog elements; and the diameter across the dog lugs being in excess of that of the barrel to ensure their retention in the barrel when the wedge is released; and a screw-stud threaded in a reduced interior extension of the barrel bore for abutting coaction with the confronting end of the wedge, to force the dog elements radially outwards, and retractable for releasing said wedge and dog elements.

CHESTER A. OSTAS.
